C. F. Kiser Inventor
By his attorney
Bralle & Co.

UNITED STATES PATENT OFFICE.

CHARLES F. KISER, OF SHIPPENSVILLE, PENNSYLVANIA.

COMBINED STOP-COCK AND CHECK-VALVE.

SPECIFICATION forming part of Letters Patent No. 470,058, dated March 1, 1892.

Application filed May 25, 1891. Serial No. 394,023. (No model.)

To all whom it may concern:

Be it known that I, CHARLES F. KISER, a citizen of the United States, residing at Shippensburg, in the county of Clarion and State 5 of Pennsylvania, have invented certain new and useful Improvements in Combined Stop-Cocks and Check-Valves; and I do declare the following to be a full, clear, and exact description of the invention, such as will enable others 10 skilled in the art to which it appertains to make and use the same, reference being had to the accompanying drawings, and to the letters of reference marked thereon, which form a part of this specification.

15 My invention relates to improvements in combined stop-cocks and check-valves for supplying water to steam or other boilers; and the invention consists in the combination and arrangement of the several parts, as will be 20 hereinafter more fully described, and specifically pointed out in the claim.

In the accompanying drawings, to which reference is had and which fully illustrate my 25 invention, Figure 1 is a vertical section of my invention. Fig. 2 is a top or plan view. Figs. 3 and 4 are details of the same.

The same designations indicate corresponding parts in all the views.

A indicates a shell, slightly conical in form, 30 provided with lateral hollow hexagonal projections B, formed integral therewith. In the shell are formed vertical rectangular slots b b', having the opposite sides cut at an angle to the other sides—that is, the upper side of the slot b' and the lower side of the slot b are cut at an angle to their respective opposite sides and are parallel. These slots register with the inner termini of the projections. Axially coincident with the shell is a plug or 35 cock C, having two openings d d' in the same perpendicular plane. The opening d' has its lower side cut at an angle to the plug and opposite in direction to the angle of the upper side of the slot b'. The opening d is in communication with the valve-seat E. It is thus apparent that by turning the plug it can be made to make or break communication between the openings d d' and the ports b b'. Secured within the shell is an annular metal- 45 lic valve-seat E, against which the lower part of a cage normally abuts.

The plug or cock C is secured to the outer

cone or shell by means of a screw-extension e of said cone and a suitable washer e' and nut e'', the extension e having the usual screw- 55 threads thereon. Within the core is an annular recess having antipodal grooves in the walls thereof, wherein the guide-rods G of the cage reciprocate. The rods G connect the head-block I with the valve H, wherein a 60 heavy check-valve O normally rests. The head-block I is connected to the threaded stem J, so that the whole cage is capable of vertical reciprocation. A washer K makes the connection permanent. A bonnet L fits over 65 the plug C and is screwed therein by means of the extension l, engaging the threaded recess l'. The bonnet L also has an upper threaded extension M, that engages a threaded cap N, whereby a stuffing-box is formed. 70

It will be understood that two variable conditions are permissible by this construction: First, the plug being in the position shown and the cage being seated, communication is established between the ports b and b' to a 75 stream of fluid of sufficient pressure to lift the ball-valve O, and, second, the plug being in the same position and the cage G H I being raised, a free communication is established 80 between the ports b and b'.

I am aware of the patent granted to E. Miller on the 28th day of April, 1874, No. 150,343, wherein openings in different planes are made in a rotary plug and a spring-depressed valve is provided to cut off communication between 85 the opposite projections. While the objects of that invention are analogous to those of mine, the constructions differ, among other things, in the substitution of a free ball-valve for the cumbrous valve therein shown. 90

I am also aware of the patent granted to L. G. Gilbert on the 7th day of April, 1885, No. 315,273; but therein no such plug as mine is shown, and the ball-valve is restrained in its motion, while in mine it is free. 95

I am also aware of the patent granted to M. B. Fisher on the 28th day of April, 1885. This invention differs from mine in two notable particulars besides structural differences: There is no plug, which is an element of my 100 invention; there is no ball-valve capable of fitting any seat, as shown in my invention, and the valve therein shown is restrained in its action, while mine is free.

Having thus fully described my improvements, what I claim is—

The combined stop-cock and check-valve herein shown and described, consisting of the shell A, having antipodal projections B, provided with openings b b', whose respective upper and lower sides are angular and parallel, the stop-cock C, having slots d d', the latter having an inclined base registering with said openings b b', the stem J, by which the altitude of the cage is altered, stepped in the

head-block I, the cage G H I, the valve II, the heavy ball-valve O, and the seat E, supporting the cage, the whole co-operating as set forth.

In testimony whereof I affix my signature in presence of two witnesses.

CHARLES F. KISER.
